UNITED STATES PATENT OFFICE.

JOSEPH SEYMOUR, OF SYRACUSE, NEW YORK.

DESIGN FOR A BADGE.

Specification forming part of Design No. **7,046**, dated December 9, 1873; application filed February 10, 1873.
[Term of Patent 7 years.]

To all whom it may concern:

Be it known that I, JOSEPH SEYMOUR, of the city of Syracuse, in the county of Onondaga and State of New York, have invented a Design for Badges, Pins, Buttons, or other insignia for a society, association, or order known as the "Patrons of Husbandry," of which the following is a specification:

The nature of my invention is fully represented in the accompanying drawing, to which reference is made.

A represents the ground-work of the design, circular in form, and of some suitable color; and B, a rim of gold, silver, or other metal surrounding the same. Upon the ground-work of the design, and occupying the central portion thereof, is the figure of a plow, in gold, silver, or other metal, represented by C, surrounded by a sheaf of wheat, in the same ma-

terial, represented by D, with the letter "P." at the left of the share of the plow, the word "of" underneath it, and the letter "H." at the right of it, all in the same material as the figures above mentioned.

I do not claim as my invention the figures of the plow, or sheaf of wheat, or the badge, pin, or button, as such.

What I do claim, and desire to secure by Letters Patent, is—

The design for a badge, pin, button, or other insignia of a society, composed of the figures of a plow, sheaf of wheat, and the letters "P. of H.," upon an appropriate ground, arranged and combined substantially as above described.

JOSEPH SEYMOUR.
